UNITED STATES PATENT OFFICE

JAMES B. LADD, OF ARDMORE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY

CENTRIFUGAL CASTING MACHINE

Application filed January 19, 1928. Serial No. 247,783.

My invention relates to machines of the de Lavaud type for the centrifugal casting of cast iron pipes. Such machines comprise a reciprocating carriage sustaining a water box and a rotatable mold, the body of which is enclosed in the water box. As heretofore constructed such machines have been provided with means for reciprocating the carriage including generally a hydraulic cylinder and piston, the speed of which is affected by a varying load, and the prime object of my invention is to provide as a carriage actuating means a constant speed motor so as to maintain the carriage at any desired speed of motion, irrespective of varying resistance.

A further object of my invention is to provide improved mechanism for reciprocating the carriage comprising a rope connected to actuate the carriage in either direction and actuated preferably by an electric motor and to provide in such driving mechanism means for preventing the carriage from striking the abutments which limit its motion with injurious or destructive force. Other objects which I have in view are to protect the rope against contact with the metal which sometimes issues from the rear end of the mold and for taking up any slack which may form in the rope in such a manner that the take up device is securely held in any position it may assume in taking up slack so that the rope cannot again become slack.

The nature of my improvements will be best understood as described in connection with the drawings which illustrate a portion of a centrifugal casting machine provided with a reciprocating carriage actuated by my improved mechanism in which drawings:

Figure 1 is a plan view of the apparatus with the carriage removed.

Figure 2 a side elevation of the apparatus with the carriage shown in place.

Figure 3 a sectional view on the line 3-3 of Fig. 2, and

Figure 4 a diagram representing the electric circuits and appliances for controlling the electric motor.

A, A indicate beams forming part of the framing of the casting machine and supporting tracks A¹ A¹. B indicates the water box

which constitutes also the carriage supported on the tracks A¹ by means of the wheels indicated at B¹. B² indicates the mold supported in the water box of the carriage, means for rotating the mold not being shown, as they form no part of the present invention. C is the runner by which molten iron is introduced into the mold; C' an extension of the runner into which metal is poured at the top, for instance, by a ladle D. E and E¹ are abutment stops to limit the travel of the motor, the abutment E being shown as provided with a hollow portion e to give clearance to the apron indicated at F, which is attached to the rear lower side of the carriage so as to deflect any metal which may issue from the mold and keep it out of contact with the rope which actuates the mold. G indicates the wire rope which is attached to the mold in such a way as to actuate it in either direction. By preference I make the attachment through springs which will permit of a slight relative movement between the carriage and the mold in either direction. As shown, the connection is made through springs H, H¹ surrounding a rod G¹ to which the ends of the rope are attached and abutting against a downwardly extending lug B³ extending from the bottom of the carriage and forked to embrace the rod as indicated in Figs. 2 and 3. The rope is actuated by a winding drum I, from which it passes over guide pulleys K, K¹ and K² and also over pulleys K³, K⁴ and K⁵, forming part of the take up mechanism to be described. The winding drum is attached to the shaft I¹ to which is also attached a worm wheel I² actuated by a worm J secured to a shaft J¹ which is actuated by an electric motor indicated at J².

It is necessary for the proper operation of the mold carriage that there should be no yield due to slack in the driving rope. I therefore provide an automatic take up mechanism and to prevent any slackening of the rope under any conditions I provide the take up mechanism with a special device which prevents its backward movement. As shown, my take up device consists of a hydraulic cylinder L, having in it a piston

L¹ from which extends a piston rod **L**² supporting at its end a take up pulley indicated at **K**⁵ located between the pulleys **K**³ and **K**⁴ and to prevent rearward motion of the take up pulley I provide a non-return valve **M**¹ in the conduit **M** through which fluid under pressure enters the cylinder **L**.

The stopping and starting of the motor in either direction is controlled by a master switch which also controls the speed of the motor and to slow up and arrest the motion of the carriage at either end of its travel so that it will not strike the abutments with injurious force I provide slow down limit switches 23 and stop limit switches 17 which are actuated by the movements of the carriage through some convenient appliance, as, for instance, lugs **N** and **N**¹. The electric circuits and appliances are clearly indicated in the diagram, Fig. 4, the parts whereof are indicated as follows: 1 is the motor armature; 2 is the direct current power supply; 3 is the shunt field; 4 is the field rheostat; 5 is the starting resistance; 6 is the slow down and accelerating contactor; 7 is a two-pole magnetic contactor and 7A being the normally closed contact of contactor 7; 8 a two-pole magnetic contactor and 8A the normally closed contact of contactor 8; 9 is a dynamic breaking resistance; 10 an operating coil for the slow down and accelerating contactor 6; 11 is the normally closed-in off position of the master switch; 12 contact of low voltage relay; 13 the operating coil for the low voltage relay; 14 is the master switch contacts closed in the first pouring or return position of master switch. 15 is the operating coil for the return contactor 8; 17 indicates the stop limit switches and 18 master switch contacts closed on the 2nd point pour and return positions of master switch; 19 is the operating coil for the high speed contactor 20; 21 is the main line knife switch; 22 is the control circuit knife switch; 23 indicates the slow down limit switches; 24 is a drum switch mechanically coupled to the master switch 14.

In operation contact 11 of master switch 14 is closed only in the "off" position of the master switch, therefore when power is applied at 2 the operating coil of low voltage relay 13 is energized and the contacts 12 in closing make operation possible through contacts 18 of master switch.

55 The carriage is of course at rest at either end of its stroke. For actuating the motor to move carriage slowly in either direction the master switch is thrown to the first point in either direction, which starts the 60 motor to a slow speed, corresponding to the setting of the field rheostat 4.

When the carriage passes the slow down limit switch 23 the motor is automatically slowed down to below normal speed by inserting armature resistance 5 and applying

full voltage to the motor shunt field 3. When the stop limit switch 17 is reached by the carriage, the motor armature 1 is disconnected from the line and the electrical breaking is obtained by inserting resistance 9 in parallel with the armature 1, thus bringing the motor to a stop.

70 Where it is desired to actuate the motor at high speed, the master switch is thrown to the second point in either direction, the limit switches operating in the same way.

75 The electric motor described is a constant speed motor and apart from the other features of my invention I consider the use of such a motor or of any constant speed motor to actuate the carriage as a distinct improvement in the type of apparatus described.

80 Having now described my invention, what I claim as new and desire to secure by Letters Patent, is:

1. In a machine for the centrifugal casting of pipes having a reciprocating mold carrying carriage, means for reciprocating the carriage comprising a rope connected to move the carriage in opposite directions and means for actuating the rope including an electric motor.

85 90 95 100 105 110 115 120 125

2. In a machine for the centrifugal casting of pipes having a reciprocating mold carrying carriage, means for reciprocating the carriage comprising a rope connected to move the carriage in opposite directions, means for actuating the rope including an electric motor and an apron secured to the rear of the carriage for protecting the rope from molten metal escaping from the end of the mold.

3. In a machine for the centrifugal casting of pipes having a reciprocating mold carrying carriage, means for reciprocating the carriage comprising a rope connected to move the carriage in opposite directions, means for actuating the rope including an electric motor, an electric circuit system for actuating the motor in either direction comprising a master switch, slow down limit switches and stop limit switches and means controlled by the movement of the carriage for actuating successively a slow down and a stop switch as the carriage approaches the ends of its reciprocatory movement.

4. In a machine for the centrifugal casting of pipes having a reciprocating mold carrying carriage, means for reciprocating the carriage comprising a rope connected to move the carriage in opposite directions, means for actuating the rope including a constant speed electric motor, an electric circuit system for actuating the motor in either direction comprising a master switch, slow down limit switches and stop limit switches and means controlled by the movement of the carriage for actuating successively a slow down and a stop switch as

the carriage approaches the ends of its reciprocatory movement.

5. In a machine for the centrifugal casting of pipes having a reciprocating mold carrying carriage, means for reciprocating the carriage comprising a rope connected to move the carriage in opposite directions, automatic means for taking up slack in the rope including a stop device for preventing 10 a backward movement of the take up mechanism and means for actuating the rope including an electric motor.
